UNITED STATES PATENT OFFICE.

ISAAC C. WOOLREY, OF GENESEO, KANSAS.

BOOK-CASE.

SPECIFICATION forming part of Letters Patent No. 447,628, dated March 3, 1891.

Application filed June 5, 1890. Serial No. 354,356. (No model.)

To all whom it may concern:

Be it known that I, ISAAC C. WOOLREY, of Geneseo, in the county of Rice and State of Kansas, have invented a new and Improved 5 Book-Case, of which the following is a full, clear, and exact description.

The object of the invention is to provide a new and improved book-case which is simple and durable in construction and adapted to 10 hold each book between two movable partitions, thus protecting and preventing injury to the books, and at the same time holding the books in place.

The invention consists in certain parts and 15 details and combinations of the same, as will be described hereinafter, and then pointed out in the claims.

Reference is to be had to the accompanying drawings, forming a part of this specification, 20 in which similar letters of reference indicate corresponding parts in both the figures.

Figure 1 is a sectional front elevation of the case on the line $x-x$ of Fig. 2. Fig. 2 is a transverse section of the same.

25 The book-case A is provided with the outer casing or shell B, comprising the back C, the sides D, top E, and bottom F. The casing B is provided with a door b and with a series of horizontally-extending shelves G, forming 30 the usual spaces H for the reception of the books. In the several spaces H are placed vertically-arranged partitions I, each provided on top and bottom with a tongue I', fitting into a correspondingly-shaped longitudinally-extending groove K, formed in the shelves G on the top and bottom, in the under side of 35 the top E, and the upper face of the bottom F, as is plainly shown in Fig. 2. The tongues I' serve to hold the partitions in place and in 40 the book-spaces H, and at the same time permit a sliding movement of the same. Each of the partitions I is also provided with an eye L, each connected with a spring N, extending longitudinally in a suitable groove O, formed 45 similar to the grooves in the shelves G, the top E, and bottom F. The ends of the springs N are fastened to the inside of the sides D, and serve to hold the partitions in proper place, at the same time permitting a slight 50 longitudinal movement of the same to accom-

modate books of varying thicknesses. Eyes P, similar to the eyes L, are arranged in the rear edge of each partition I, and the several eyes of one set of partitions in a space H are connected with a spring Q, held in a groove 55 R formed in the inner face of the back C of the casing B. The ends of the several springs Q are secured to the sides D and serve the same purpose as the springs N. The several sets of springs N and Q for each set of partitions hold the latter firmly in place and permit an easy and parallel movement of the same. The springs may also be made in sections, their ends connecting with the eyes of adjoining partitions. 65

In placing a book into the book-case, the operator presses one partition to one side or two adjoining partitions apart to make sufficient room according to the thickness of the book. The latter is then shoved into the space, 70 and the operator letting go the partitions, the latter are forced onto the covers of the book and hold the latter in place. A number of books may be placed between two adjacent partitions, if desired. Thus it will be seen 75 that each book is securely held in place in the book-case, even if the latter has the respective shelf not filled from one end to the other. By holding the books between two partitions injury to the covers is entirely prevented. 80 The springs are embedded in grooves, so that the books do not touch the same, thereby avoiding injury to springs and books.

Having thus described my invention, what I claim as new, and desire to secure by Letters Patent, is—

1. The combination, with a book-case, of a series of vertically-arranged partitions fitted to slide freely between the shelves thereof and horizontally-arranged springs connected 90 to the several partitions and holding them yieldingly apart, substantially as described.

2. The combination, with a book-case provided with grooved top and bottom and grooved shelves, of vertical partitions fitted 95 to slide freely in the grooves of the top and bottom and the shelves and horizontally-arranged springs connected to the partitions and holding them yieldingly apart, substantially as described. 100

3. In a book-case, the combination, with the casing or shell having grooved top and bottom, of grooved shelves arranged in the said shell, partitions arranged in the said shell and having tongues fitting into the said grooves, and springs held in grooves in the casing and shelves and connected with the said partitions to permit the latter to slide, substantially as shown and described.

ISAAC C. WOOLREY.
